(57) **CLAIM**

The ornamental design for a tool-side harness plug as shown and described.

DESCRIPTION

FIG. 1 is a first perspective view of a tool-side harness plug according to a first embodiment.

FIG. 2 is a front side view of the tool-side harness plug of FIG. 1.

FIG. 3 is a first perspective view of a tool-side harness plug according to a second embodiment.

FIG. 4 is a front side view of the tool-side harness plug of FIG. 3.

FIG. 5 is a first perspective view of a tool-side charger paddle according to a third embodiment.

FIG. 6 is a front side view of the tool-side charger paddle of FIG. 5.

FIG. 7 is a first perspective view of a tool-side charger paddle according to a fourth embodiment; and,

FIG. 8 is a front side view of the tool-side charger paddle of FIG. 7.

The ornamental design which is claimed is shown in solid lines.

The broken lines in the drawings depict portions of the tool-side harness plug that form no part of the claimed design.
